CLAIM

We claim the ornamental design for a spectrometer, as shown and described.

DESCRIPTION

FIG. 1 is a front, right perspective view of an embodiment of a spectrometer showing our new design, wherein an arm is in a closed position;

FIG. 2 is a front elevation view of the spectrometer of FIG. 1;

FIG. 3 is a left elevation view of the spectrometer of FIG. 1; FIG. 4 is a right elevation view of the spectrometer of FIG. 1;

FIG. 5 is a top plan view of the spectrometer of FIG. 1; FIG. 6 is a front, right perspective view of another embodiment of a spectrometer showing our new design, wherein an arm is in a closed position;

FIG. 7 is a front elevation view of the spectrometer of FIG. 6;

FIG. 8 is a left elevation view of the spectrometer of FIG. 6; FIG. 9 is a right elevation view of the spectrometer of FIG. 6; and,

FIG. 10 is a top plan view of the spectrometer of FIG. 6. The broken lines in the figures form no part of the claimed design.
